UNITED STATES PATENT OFFICE.

SAMUEL SUEKOFF, OF CHICAGO, ILLINOIS.

CUSHION-COVER CONSTRUCTION.

Application filed July 29, 1925. Serial No. 46,754.

To all whom it may concern:

Be it known that I, SAMUEL SUEKOFF, a citizen of the United States of America, and a resident of Chicago, county of Cook, and State of Illinois, have invented a certain new and useful Improvement in Cushion-Cover Constructions (Case C), of which the following is a specification.

This invention relates to improvements in cushion construction, and more particularly to an efficient and economical method of fabricating and assembling cushion covers adapted for use with resilient filling units such as springs or cushioning material.

As commonly made, a cushion cover consists of pieces of fabric, usually burlap, cut and sewn together not only to form the bottom, top and side walls, but a series of individual cells or pockets within the outer walls, and adapted to contain the resilient material units. The problem of making cushion covers is not merely one of structure, but it is one of the methods of preparing the material for sewing, and then sewing the pieces together, so that the cushion can be loaded with resilient material with the least amount of time and labor.

In companion applications filed by me on the 18th and 24th days of July, 1925, and bearing Serial Nos. 44,416 and 45,735, respectively, I have shown and described improved constructions of cushion cover and methods of manufacturing the same, including the use of so-called "combs" or integral strips of material used for forming certain side walls of individual compartments. In the present invention I provide an improved construction wherein similar combs form all the walls of the individual compartments being incorporated in the completed cover with greater facility and less operating costs and also affording a lighter and more readily ventilated cover construction.

Of such a nature is the present invention, and its applicability to the art will be better appreciated as the process is disclosed with the aid of the accompanying drawings, in which—

Figure 1 is a perspective view showing a portion of the material forming one of the covers, said material being marked off for subsequent sewing of partition strips along predetermined lines.

Figure 2 is a similar view of the piece shown in Figure 1 but illustrating an arrangement of combs as applied to the mate-

rial forming one of the covers to form a base.

Figure 3 is a perspective view of the top cover piece with the combs sewed thereto. 60

Figure 4 is a detailed view in vertical section of the complete assembled cushion, taken on line 4—4 of Figure 2.

Figure 5 is a view similar to Figure 4, but taken at right angles thereto. 65

Figure 6 is a detailed view illustrating the method of manufacturing the combs before sewing into the structure.

Figure 7 is a detail view in vertical section of a modified form of my invention. 70

Regarding first the structure of the cushion as a whole, a portion of which is shown in Figures 4 and 5, the same consists of top and bottom pieces 1 and 2 of suitable fabric, such as burlap, sewn together at the edges in a seam 3 extending around the cushion between the top and bottom thereof, the marginal portions of these pieces forming a boxing or end and side walls of the cushion. 80

Within the outer covering formed by the pieces 1 and 2 are a series of continuous combs extending the full length (or width) of the cushion with the longitudinal edges thereof sewn to the top and bottom cover pieces. These combs are parallel with each other and divide the interior space of the cushion into a plurality of full length compartments. Each of these combs is made up of a base 4^a and a plurality of tabs 4^b connected therewith, said tabs extending the full height of the cushion, as will herein-after appear. 85

In connection with the compartments formed between the combs 4 and arranged transversely thereof is provided a plurality of division walls 5 which divide the cushion into a plurality of smaller compartments or cells. In the finally completed cushion each of these division walls 5 is made up of two parts 5^a—5^a sewn together adjacent their center in a seam 5^b as will hereinafter appear. Each set of tabs 5^a—5^a are part of oppositely disposed combs indicated generally by numerals 7 and 8 and arranged 100 transversely of the combs 4 but each being of substantially one-half the height of the latter combs as shown in Figures 2 and 3. The lower combs 7 are attached to the bottom cover 2, as shown in Figure 2, transversely of the combs 4 while the upper combs are attached to the upper cover 1 as

shown in Figure 3. The various steps taken in constructing the completed cushion will now be described.

The first step in the process is to provide 5 a pair of similar top and bottom pieces 1 and 2 having sewing lines 10—10 arranged at right angles to each other to outline the 10 size of the compartments or cells of the completed cushion. To one of these pieces of 15 material, as for instance, the bottom piece 2, as shown in Figure 2, is secured a set of combs 4 and 7, each set being parallel to each other and arranged at right angles to the other set, as shown in Figure 2. As a preferred 20 method of construction of these combs, described and specifically claimed in my companion application executed July 17, 1925, the combs 4, 7, and 8 may all be constructed in a similar manner, so that a description 25 of one set of combs, as, for instance, the comb 7 will serve to illustrate the construction of all. Thus, as shown in Figure 6, a single strip of material 9 is provided, being of a width substantially equal 30 to the height of one set of tabs 5^a plus the height of two bases 7^a. This strip is marked with two rows of sewing lines 12—12 parallel to and adjacent each side margin, and a second row of sewing lines 5^c is marked 35 parallel to and spaced inwardly from the first named pair of sewing lines 12—12. The strip is then cut along transverse lines 9^a and longitudinal lines 9^b so as to form two sets of combs, in which the width of each of the 40 tabs 5^a is the same as the notches 5^b. The cutting operation may be carried out in any suitable manner, as, for instance, by rotary cutting machines of the type well known in the art, which may be readily adapted for 45 the purpose. The combs formed as described, are then cut into suitable lengths and secured to their respective covers.

In the case of the combs 7, the same is secured to the cover 2 along sewing lines 50 12—12 previously marked on the base 7^a and close to the bottom margin of the notches 5^b now formed therein. As will be seen from Figure 2, an entire series of strips or combs 7 are sewn in parallel relation along adjacent sewing lines 10 on the base 2 in this manner, and a series of combs 8 are also secured to the cover 1, it being understood 55 that these combs are also made in pairs from a single piece of material as already described in connection with the combs 7, but the tabs 4^a thereof being substantially twice the height of the corresponding tabs 5^a of combs 7. For the purposes of my invention, it makes little difference which set of combs 60 4 and 7 are applied first to the base piece 2. In either case, the first set of combs, as in the present instance, the combs 7, are applied directly to the base piece and then the second set of combs, in the present instance 65 the combs 4, are then applied to the base 2

along seams 4^c, these seams following the transverse sewing lines 10 and passing through the centers of aligned tabs 5^a—5^a of combs 7 as shown in Figure 2.

Referring now to the top piece 1, a plurality of combs 8 of construction similar to the shorter combs 7 are arranged along parallel seams 13 to correspond with the similar combs 7 secured to the bottom cover 2. The arrangement is such that the top 75 cover 1 with its combs 8 assembled thereon may be fitted over the bottom cover 2 with its combs 7 and 4 in position to be secured together in finally assembled form, as shown 80 in Figures 4 and 5.

A preferred method of securing these parts may be described as follows:

Starting along one edge of the cushion parallel with the longer combs 4, the cells or compartments are completed progressively 85 in rows towards the opposite edge of the cushion substantially as follows: The first row of tabs 5^a—5^a of the abutting combs 7 and 8 between the first comb 4 and the cushion edge are sewn together along sewing lines 5^c which were previously marked on the continuous strip A from which said combs were cut as hereinabove described. The free upper edges of the tabs 4^b—4^b of the first comb 4 are then sewn to the upper 90 piece 1 along sewing lines 4^c (previously marked in the same manner as sewing line 5^c of comb 7) said sewing lines 4^c registering with the corresponding sewing lines 10—10 on the upper cover piece 1, to complete the 100 first row of cells.

The assembling operation may then be continued as follows: The second row of 105 pairs of abutting tabs 5^a—5^a adjacent the first comb 4 are joined along seams 5^c, and the second comb 4 is then sewn to the top cover 1 to complete the second row of compartments, and this operation is repeated until all of the compartments are formed. One or more of the side and end walls may 110 be closed or boxed along seams 3 at any time in the process, although, of course, the cushion is not finally closed or boxed along all sides until the individual compartments 115 are loaded with suitable resilient material, as will hereinafter be described.

One of the principal advantages of the construction above described, is the provision of the combs 4, 7, and 8 in such a manner that their bases may be each connected to their respective covers in a single sewing operation. Furthermore, the provision for joining the tabs 5^a—5^a adjacent the center of the cushion is preferable inasmuch as the covers 1 and 2 may be drawn together or flattened during the assembling operation in such a manner as to permit each pair of tabs 5^a—5^a to be folded outwardly and the other unassembled parts folded back, so that 120 said tabs project from the part of the cover 125 130

already assembled and may thus be quickly sewn together along their sewing lines 5^c.

A further advantage of the construction herein described, is that the sides of all the partitions forming the compartments are skeletonized, being closed only adjacent the center lines of each compartment. The construction manifestly affords maximum economy in material and yet the connecting strips are fully wide enough for practical purposes, especially when each compartment is to be loaded with helical springs, the connecting strips between the adjacent compartments being arranged so as to retain the springs in their proper place. Furthermore, the separate compartments being open at all four corners, the cushion is extremely light and is readily ventilated through all portions thereof, and furthermore affords maximum flexibility that is desirable to rapid and convenient loading of the cushion with resilient material such as springs.

As a preferred means of loading the resilient springs comprising helical coils of wire in the separate compartments, an implement known as a loading tool is used in which a number of springs equivalent to the number constituting a single row, are held flatly compressed within the tool. The tool is then inserted into the open end of the cushion and along one side of each longitudinal compartment formed between successive partition strips 4, the tool being held so that the flattened springs pass through the openings between the partition strips and the adjacent edges of the tabs. It will be understood, however, that a cushion cover constructed in accordance with my invention may also be loaded with other resilient cushioning means.

A modified form of my invention utilizing a plurality of transversely disposed combs, is shown in Figure 7. In this case the combs 14 and 17, as applied to the base 2, correspond to the combs 4 and 7 in Figure 2 but in this instance the two sets of combs are of equal height and are both connected directly to the top piece 1. The process of assembling this form is substantially the same as that already described in connection with the preferred form excepting, of course, that no combs are initially attached to the upper piece 1.

As before explained, the process of assembling the cushion cover with partition strips consisting entirely of combs, results in a marked saving of time, labor and material in the manufacture of the cover, eliminating the sewing of a multitude of short seams, each of which may be a separate sewing operation.

I claim as my invention:

1. A cushion cover construction compris-

ing top and bottom cover pieces, and connecting members therebetween forming rectangular cells, said connecting members comprising a plurality of combs, each consisting of a single piece of material initially sewn along one edge of one of said cover pieces and provided with spaced cuts extending from the free outer edge substantially down to said sewn edge, said combs being arranged in sets disposed at right angles to each other along lines intersecting the aligned cut portions of both sets of combs. 75

2. A cushion cover construction comprising top and bottom pieces, and connecting members therebetween forming rectangular cells, said connecting members comprising a plurality of combs, each consisting of a single piece of material initially sewn along one edge of one of said cover pieces and provided with spaced cuts extending from the free outer edge substantially down to said sewn edge to form alternate notches and 85 tabs of substantially equal width, said combs being arranged in sets disposed at right angles to each other along lines intersecting the aligned cut portions of both sets of combs. 90

3. A cushion cover construction comprising top and bottom pieces, and connecting members therebetween forming rectangular cells, said connecting members comprising a plurality of combs, each consisting of a single piece of material initially sewn along one edge to one of said cover pieces and provided with spaced cuts extending from the free outer edge substantially down to said sewn edge, one of said combs being substantially twice the height of the opposite or shorter set of combs and connected directly to the opposite cover piece, and a set of combs corresponding to said shorter set of combs, sewn along one edge to said opposite 105 cover pieces and having their adjacent edges connected in registering engagement to said first named sets of shorter combs.

4. A cushion cover construction comprising top and bottom pieces and connecting members therebetween forming rectangular cells, said connecting members comprising two sets of combs of equal height, each comb consisting of a single piece of material initially sewn along one edge to one of said 110 cover pieces and provided with spaced cuts extending from the free outer edge substantially down to said sewn edge, said sets of combs being arranged at right angles to each other with the base portions mutually 115 intersecting each other on lines passing through the respective spaced cuts thereof. 120

Signed at Chicago this 27 day of July, 1925.

SAMUEL SUEKOFF.
